13 Claims

ABSTRACT OF THE DISCLOSURE

A lamp receptacle for use in a lamp socket assembly adapted to receive an elongated lamp, the receptacle including electrical contact means within the receptacle adapted to connect one end of an elongated lamp to a source of electric energy, and ejector means associated with the receptacle for ejecting the elongated lamp from the receptacle in a direction transverse to the longitudinal axis of the lamp. Preferably, the lamp receptacle includes a terminal block having a body portion and a lamp receiving portion and the body portion has passage means for receiving the ejector means. In one preferred embodiment of the invention, spring means are provided within the passage means for biasing the ejector means to a non-ejecting position while allowing the ejector means to be manually operated to move a finger portion thereof into the lamp receiving portion to eject one end of the lamp from the receptacle. In another preferred embodiment of the invention, the passage means is partially closed off at one end by a portion of the electrical contact means to limit movement of the finger portion into the lamp receiving portion and to assist in retaining the ejector means in the passage means.

BACKGROUND OF THE INVENTION

(1) Field of the invention

The field of this invention is that of lamp receptacles particularly lamp receptacles adapted to receive one end of an elongated lamp, such as a fluorescent lamp. The field of this invention is also that of a lamp receptacle adapted to snap fittingly receive one end of an elongated lamp and having ejector means associated with the receptacle for ejecting the one end of the elongated lamp from the receptacle in a direction transverse to the longitudinal axis of the elongated lamp.

(2) Description of the prior art

In some prior art lamp socket assemblies, particularly fluorescent lamp fixtures, an elongated lamp is removed from the lamp receptacle either by pushing the lamp axially into the receptacle and then rotating the lamp to free it from the receptacle, or by pulling the end of the lamp directly out of the lamp receptacle in a direction transverse to the longitudinal axis of the lamp. In other prior art lamp socket assemblies, the elongate lamp is first rotated before being removed from the receptacle in a direction transverse to the longitudinal axis of the lamp. However, in these prior art lamp receptacles, the means for retaining and releasing the elongated lamp have not always been adequate for a lamp socket assembly which is located in a confined area, or otherwise mounted in a manner which makes it difficult to insert and remove the elongated lamp into and out of the lamp socket assembly.

SUMMARY OF THE INVENTION

In view of the need for means to effect, or assist in effecting, removal of the end portion of an elongated lamp, such as a fluorescent lamp, from a lamp receptacle,

2

the present invention provides a lamp receptacle having ejector means associated therewith for ejecting one end of the elongated lamp from the receptacle in a direction transverse to the longitudinal axis of the lamp.

5 In one preferred embodiment of the invention, the lamp receptacle includes a terminal block having a lamp receiving portion and a body portion which extends from the lamp receiving portion to an end surface of the terminal block, the body portion having passage means therein extending from the end surface to the lamp receiving portion, and this passage means is adapted to receive the ejector means.

In a further preferred embodiment of the invention, the ejector means includes an elongated button portion 15 and a finger portion, the button portion having a first end which is received in the passage means and a second end which extends out of the body portion beyond the end surface, and the finger portion having a first end connected to the first end of the button portion and a second end which is adapted to extend into the lamp receiving portion.

In a still further preferred embodiment of the invention, resilient means are provided in the passage means for biasing the ejector means to a non-ejecting position.

25 In another preferred embodiment of the invention, the electrical contact means secured in the lamp receiving portion includes a U-shaped spring clip member adapted to snap fittingly receive one end of the elongated lamp with the finger portion of the ejector means adapted to 30 extend into the lamp receiving portion adjacent the U-shaped clip member to engage the one end of the lamp to eject the lamp from the lamp receiving portion in a direction transverse to the longitudinal axis of the elongated lamp.

35 In still another preferred embodiment of the invention the passage means is partially closed off at one end by a portion of the electrical contact means to limit movement of the finger portion into the lamp receiving portion and to assist in retaining the ejector means in the passage 40 means.

One object of this invention is to provide a simple means for ejecting an end portion of an elongated lamp received in a lamp receptacle from the receptacle.

Another object of this invention is to provide an ejector 45 means associated with a lamp receptacle for ejecting an elongated lamp from the receptacle in a direction transverse to the longitudinal axis of the lamp.

Other objects and advantages of this invention will 50 become more apparent from the following description taken in conjunction with the accompanying drawings.

BRIEF DESCRIPTION OF THE DRAWINGS

FIG. 1 is a front elevational view of a preferred embodiment of the lamp receptacle of this invention;

55 FIG. 2 is a top plan view of the lamp receptacle shown in FIG. 1;

FIG. 3 is a sectional view taken along lines 3—3 of FIG. 2 and showing one end of a tubular lamp in phantom line; and,

60 FIG. 4 is a modified version of the ejector means shown in FIG. 3.

DESCRIPTION OF THE PREFERRED EMBODIMENTS OF THE INVENTION

65 A lamp receptacle is generally indicated at 10 in FIG. 1. The lamp receptacle includes a terminal block 11 having a lamp receiving portion or receptacle portion 12 and a body portion 14. Preferably, the terminal block 11 is made of an insulating material, such as a moldable plastic material. The lamp receiving portion 12 has an opening 16 which is defined by three wall portions 18, 19 and

20 extending from the body portion 14 and by an inner end surface 21 of the body portion 14. One end cap 22 of an elongated lamp 23 (shown in phantom lines in FIG. 3) is received in the opening 16. It is to be understood that the other end of the lamp (not shown) is received in a similar or identical receptacle 10.

Electrical contact means 24 are secured within said opening 16. Preferably, the electrical contact means include an inverted T-shaped, spring contact member 26 and a generally U-shaped, spring clip member 28 as shown in FIGS. 1 to 3.

The cross portion 30 (FIG. 2) of the inverted T-shaped spring contact member 26 forms a base mounting portion for the spring contact member 26. The upright portion 32 of the spring contact member 26 is connected to, and extends from, the cross portion 30 and is bent over to provide a spring contact 34 for engaging the end cap 22 of the elongated lamp 23, e.g. a fluorescent lamp. As shown in FIG. 2, the cross or base mounting portion 30 is secured to the inner end surface 21 by means of two rivets 35 and 36. Preferably, a wire conductor 38 from a source of electric energy is connected by means of an eyelet type lug 39 to one of the rivets, such as to rivet 36 as shown in FIG. 2. In a preferred embodiment of the invention, part of end surface 21 is recessed, as at 40 (FIG. 3), to form a channel for receiving and locating the cross or base portion 30, and for spacing and insulating the cross portion 30 from spring clip member 28.

The U-shaped spring clip member 28 comprises a bight portion 41 (FIG. 1) and two leg portions 42 and 43. The outer ends 44 and 45 of the leg portions 42 and 43 are biased against each other so that leg portions 42 and 43 provide resilient means for snap fittingly receiving and electrically contacting the end portion 22 of the lamp 23. The bight portion 41 is secured to the inner end surface 21 of the body portion by a rivet 46 as shown in FIGS. 1 and 3. Preferably, a wire conductor 47 from a source of electric energy is connected by means of an eyelet type lug 48 to a rivet 46, and held in place by a staked over end 51 of the rivet 46, as shown in FIG. 3. Preferably, the rivets 35, 36 and 46 are short, and are received through bores formed in the body portion 14. These bores have relatively deep counterbores, such as counterbore 49 of bore 50 (FIG. 3), whereby the end (or heads) of the rivets 35, 36 and 46, such as end 52 of the rivet 46 will be virtually isolated, i.e. insulated, from contact with metal which could cause a short or ground. If desired, an insulating material may be inserted in the counterbore 49 (and in similarly formed counterbores provided for rivets 35 and 36) to further insulate the end of the rivet 46 (and similarly, the ends of rivets 35 and 36). Since all the bores and counterbores are formed essentially the same way only one bore 50 and one counterbore 49 are shown in the drawings.

In the embodiment shown, the body portion 14 of terminal block 11 is provided with passage means 55 which extends from the inner end surface 21 of the body portion 14 to the outer end surface 57 of the body portion 14. An ejector means 56 is received in the passage means 55. Preferably the ejector means 56 is formed or made of an insulating material, such as moldable plastic material. A recess 58 is provided in the body portion 14 and extends from one end 59, opening into the lamp receiving portion 12, to a closed end 60. The closed end 60 is located at a point in the body portion 14 which is spaced from the outer end surface 57. A short, wall portion 61 is defined by, and between, the outer end surface 57 of the body portion and the closed end 60 of the recess 58. Wall portion 61 forms a stop means for limiting the distance which the ejector means 56 can extend beyond said end surface and for assisting in retaining the ejector means 56 in the passage means 55, as will be hereinafter explained.

The ejector means 56 (FIG. 3) includes an elongated button portion 67 and a finger portion 69 connected to

the button portion 67. One end 70 of the button portion 67 is received within the passage means 55 while the other end 71 of the button portion 67 extends out of the body portion 14 beyond the outer end surface 57. One end 72 of the finger portion 69 which is connected to the one end 70 of the button portion 67 is offset from the one end 70, i.e. the longitudinal axis of the finger portion 69 is spaced from the longitudinal axis of the button portion 67. The other end 73 of the finger portion 69 is adapted to extend into the lamp receiving portion 12 and is located for movement in the region or space between the spring contact 34 of the spring contact member 26 and the leg portions 42 and 43 of the spring clip member 28. As shown in FIG. 3 the one end 72 of the finger portion 69, offset from the one end 70 of the button portion 67, forms a shoulder which is adapted to engage wall portion 61.

A spring 75 (FIG. 3) is received within the passage means 55 and is disposed between the one end 70 of the button portion 67 and the bottom surface 76 of the cross or base mounting portion 30 of the spring contact member 26, to bias the ejector means 56 to a non-ejecting position with the one end 72 of the finger portion 69 engaging the wall portion 61.

The receptacle 10 is particularly adapted for use with a fluorescent lamp where the end cap 22 has a metal ring 77 (shown in phantom lines in FIG. 3) on the periphery of the end cap 22 which forms one contact of the lamp. A rounded metal projection 78 is located on the end surface of the end cap and forms another contact of the lamp. When the lamp 23 is inserted in a lamp socket assembly having two lamp receptacles 10, each end cap of the lamp is snap fittingly received between the end portions 44 and 45 of the U-shaped spring clip member 28 of each receptacle 10. The end portions 44 and 45 provide an electrical connection to the metal ring 77 of the end cap 22 received therebetween while the spring contact 34 of the spring contact member 26 provides an electrical connection to the rounded projection 78. To remove the lamp from the lamp receptacle 10 one merely pushes the button portion 67 of the ejector means 56 into the body portion 14. This will result in movement of the finger portion 69 into the lamp receptacle portion 12 between spring contact 34 and the leg portions 42 and 43 whereby the second end 73 of the finger portion 69 will engage the end cap 22 of the lamp 23 and force the lamp out of the lamp receptacle 10.

In FIG. 4, a modified ejector means 56a is shown where the button portion 67a is provided with a flange portion 80 which extends from the one end 70a of the button portion 67a on the side of the button portion 67a which is opposite the finger portion 69a. When positioned in passage means 55, the flange 80 extends toward the lamp receiving portion 12. Preferably, the outer end 81 of the flange 80 is closer to the one end 70a of the button portion 67a than is the second end 73a of the finger portion 69a so that, when the ejector means is operated, the flange 80 will not prevent the finger portion from being pushed into the lamp receiving portion 12 to eject the end of a lamp in the lamp receiving portion 12 from the receptacle 10. The flange 80 and part of the finger portion 69a form a guideway 82 for receiving and guiding spring 75a. When the ejector means 56a is operated by pushing the button portion 67a into the passage means 55, the spring means 75a is compressed between the one end 70a of the button portion and the bottom surface 76 of the cross or base portion 30 while the guideway 82 inhibits and usually prevents buckling and possible jamming of the spring 75a within the passage means 55.

It will thus be seen, by reference to the foregoing specification and to the appended claims, that the present invention provides a novel ejector means for a lamp receptacle having a number of advantages and characteristics, including those pointed out herein and others which are inherent in the invention.

I claim:

1. A lamp receptacle for use in a lamp socket assembly adapted to receive an elongated lamp, said receptacle including a terminal block having a lamp receiving portion and a body portion which extends from said lamp receiving portion to an end surface of the terminal block, said body portion having passage means therein extending from said end surface to said lamp receiving portion, electrical contact means in said lamp receiving portion for connecting one end of said elongated lamp to a source of electric energy, and ejector means received in said passage means for ejecting said elongated lamp from said receptacle in a direction transverse to the longitudinal axis of said elongated lamp, said ejector means including an elongated button portion having a first end which is received in said passage means and a second end which extends out of said body portion beyond said end surface, and a finger portion having a first end connected to said first end of said button portion and a second end which is adapted to extend into said lamp receiving portion, said finger portion being offset from, and extending along, one side of said button portion, said electrical contact means being secured within said lamp receiving portion in such a manner that a portion of said electrical contact means closes off a portion of said passage means thereby forming a partial closure for said passage means, said partial closure being adapted to limit movement of said finger portion into said lamp receiving portion and to assist in retaining said ejector means in said passage means, a spring positioned within said passage means between said partial closure and said first end of said button portion to bias said button portion toward said end surface, said button portion having a flange portion on the side of said button portion opposite said finger portion, said flange portion extending from said one end of said button portion toward said lamp receiving portion, the outer end of said flange portion being adapted to engage said partial closure to limit inward movement of said button portion into said passage means when said button portion is pushed into said passage means against said spring, and said flange portion and said finger portion forming a guideway for inhibiting buckling and possible jamming of said spring when said button portion is pushed into said passage means.

2. A lamp receptacle for use in a lamp socket assembly adapted to receive an elongated lamp, said receptacle including a terminal block having a lamp receiving portion and a body portion which extends from said lamp receiving portion to an end surface of the terminal block, said body portion having passage means therein extending from said end surface to said lamp receiving portion, electrical contact means in said lamp receiving portion for connecting one end of said elongated lamp to a source of electric energy, and ejector means received in said passage means for ejecting said elongated lamp from said receptacle in a direction transverse to the longitudinal axis of said elongated lamp, said ejector means including an elongated button portion having a first end which is received in said passage means and a second end which extends out of said body portion beyond said end surface, and a finger portion having a first end connected to said first end of said button portion and a second end which is adapted to extend into said lamp receiving portion, said electrical contact means including an inverted, T-shaped, spring contact member having a cross-portion and a generally upright portion connected to said cross-portion, said cross-portion being secured within said lamp receiving portion over said passage means so as to form a partial closure for said passage means, and said partial closure being adapted to limit movement of said ejector means into said lamp receiving portion and to assist in retaining said ejector means within said body portion.

3. A lamp receptacle as set forth in claim 2 wherein said upright portion extends from said cross-portion ad-

jacent to the remaining open portion of said passage means, whereby, when said ejector means is operated by pushing said button portion into said passage means, said finger portion will be moved into said lamp receiving portion along and adjacent to, but spaced from, said upright portion to engage an end cap, of said elongated lamp received in said receptacle, to eject said lamp from said receptacle.

4. A lamp receptacle as set forth in claim 2 wherein said electrical contact means further includes a U-shaped, spring clip member having a bight portion which is secured in said lamp receiving portion and two leg portions which extend in the same general direction as said upright portion of said spring contact member, said bight portion being spaced from, and generally parallel to, said cross-portion of said spring contact member with the open portion of said passage means being disposed between said bight portion and said cross-portion, said leg portions being biased toward each other to provide resilient lamp contact and holding means adapted to snap fittingly receive and retain an end cap of said elongated lamp and said end cap is easily forced out of engagement with said leg portions by pushing said button portion into said passage means to cause said finger portion to extend into said lamp receiving portion to engage said end cap to force said lamp out of said receptacle.

5. A lamp receptacle as set forth in claim 2 wherein said cross portion closes off a portion of said passage means, said finger portion is offset from said button portion whereby said one end of said finger portion forms a shoulder on said ejector means, a stop means is provided in said passage means for engaging said shoulder to limit movement of said ejector means in said passage means and a spring is disposed between said one end of said button portion and said cross portion to bias said button portion out of said body portion with said shoulder engaging said stop means.

6. A lamp receptacle for use in a lamp socket assembly adapted to releasably receive an elongated lamp, said receptacle including a terminal block having a lamp receiving portion and a body portion which extends from said lamp receiving portion to one end surface of said terminal block, said body portion having passage means therein extending from said end surface to said lamp receiving portion, said lamp receiving portion having electrical contact means therein for connecting one end of said elongated lamp to a source of electric energy, and ejector means received in said passage means for ejecting said elongated lamp from said receptacle in a direction transverse to the longitudinal axis of said elongated lamp, said ejector means including an elongated ejector member having an elongated button portion and an elongated finger portion, said button portion having a first end which is received in said passage means and a second end which extends out of said body portion beyond said end surface, and said finger portion being laterally offset from said button portion such that the longitudinal axis of said finger portion is offset from the longitudinal axis of said button portion, and having a first end connected to said first end of said button portion and a second end which is adapted to extend into said lamp receiving portion, first stop means at the end of said passage means opening onto said end surface for engaging said first end of said finger portion to limit outward movement of said button portion beyond said end surface, second stop means at the end of said passage means opening into said lamp receiving portion for stopping movement of said first end of said button portion toward said lamp receiving portion to limit movement of said finger portion into said lamp receiving portion, and spring means positioned within said passage means between said second stop means and said first end of said button portion for biasing said ejector member to a non-ejecting position.

7. A lamp receptacle as set forth in claim 6 wherein said body portion of said terminal block has an elongated

recess therein opening along its length into, and forming part of, said passage means, said recess extending from a first end, which opens into said lamp receiving portion, to a closed second end which is spaced from said end surface, said recess being adapted to receive said finger portion of said ejector means.

8. A lamp receptacle as set forth in claim 7 wherein a wall portion is defined by and between said end surface of said body portion and said closed end of said recess, said wall portion forming said first stop means for limiting the distance which said button portion can extend beyond said end surface and for assisting in retaining said ejector member in said passage means.

9. A lamp receptacle as set forth in claim 6 wherein a portion of said electrical contact means closes off a portion of said passage means thereby forming said second stop means for limiting movement of said finger portion into said lamp receiving portion and for assisting in retaining said ejector member in said passage means.

10. A lamp receptacle as set forth in claim 6 wherein said button portion has a flange portion on the side of said button portion opposite said finger portion, said flange portion extending from said one end of said button portion toward said lamp receiving portion, the outer end of said flange portion being adapted to engage said second stop means to limit inward movement of said button portion into said passage means when said button portion is pushed into said passage means against said spring means, and said flange portion and said finger portion form a guideway for inhibiting buckling and possible jamming of said spring means when said button portion is pushed into said passage means.

11. A lamp receptacle as set forth in claim 6 wherein said electrical contact means includes an inverted, T-shaped, spring contact member having a cross-portion and a generally upright portion connected to said cross-portion, said cross-portion being secured within said lamp receiving portion over said passage means to form a partial closure of said passage means, said partial closure defining said second stop means.

12. A lamp receptacle as set forth in claim 11 wherein said upright portion extends from said cross-portion adjacent to the remaining open portion of said passage means, whereby, when said ejector means is operated by pushing

5 said button portion into said passage means, said finger portion will be moved into said lamp receiving portion along and adjacent to, but spaced from, said upright portion to engage to end cap, of said elongated lamp received in said receptacle, to eject said lamp from said receptacle.

13. A lamp receptacle as set forth in claim 11 wherein said electrical contact means further includes a U-shaped, spring clip member having a bight portion which is secured in said lamp receiving portion and two leg portions which extend in the same general direction as said upright portion of said spring contact member, said bight portion being spaced from, and generally parallel to, said cross portion of said spring contact member with the open portion of said passage means being disposed between said bight portion and said cross portion, said leg portions being biased toward each other to provide resilient lamp contact and holding means adapted to snap fittingly receive and retain an end cap of said elongated lamp and 15 said end cap is easily forced out of engagement with said leg portions by pushing said button portion into said passage means to cause said finger portion to extend into said lamp receiving portion to engage said end cap to force said lamp out of said receptacle.
